United States Patent Office

Des. 213,656

Patented Mar. 25, 1969

213,656

BICYCLE SEAT

Dick Lee Brown and Nora Deloris Brown, both of 1906
Chapman Ave., Olivehurst, Calif. 95961, and Ernest
R. Comstock, 5304 Sandstone St., Carmichael, Calif.
95608

Filed May 29, 1968, Ser. No. 12,124

Term of patent 14 years

Int. Cl. D12—11, 14

U.S. Cl. D90—16

FIGURE 1 is a side elevational view of a bicycle seat, showing our new design, the opposite side being substantially similar in appearance;

FIGURE 2 is a top plan view;

FIGURE 3 is a front elevational view;

FIGURE 4 is a rear elevational view; and,

FIGURE 5 is a bottom plan view.

We claim:

The ornamental design for a bicycle seat, as shown and described.
